UNITED STATES PATENT OFFICE.

GEORGE A. MEAD, OF MANSFIELD, OHIO.

SUSPENSION DEVICE FOR TROLLEY-WIRES OR OTHER CONDUCTORS CARRYING CURRENTS OF HIGH VOLTAGE.

No. 801,921.

Specification of Letters Patent.

Patented Oct. 27, 1908.

Application filed December 2, 1904. Serial No. 235,153.

To all whom it may concern:

Be it known that I, GEORGE A. MEAD, a citizen of the United States, residing at Mansfield, in the county of Richland and State of Ohio, have invented a new and useful Suspension Device for Trolley-Wires or other Conductors Carrying Currents of High Voltage, of which the following is a specification.

10 This invention relates to suspension devices for trolley wires or other conductors carrying currents of high voltage.

The object of the invention is to provide a construction which is simple and efficient for suspending trolley wires and other conductors carrying currents of high voltage.

Other objects of the invention will appear more fully hereinafter.

The invention consists substantially in the construction, combination, location and arrangement of parts, all as will be more fully hereinafter set forth, as shown in the accompanying drawings, and finally pointed out in the appended claims.

25 Referring to the accompanying drawings, and to the various views and reference signs appearing thereon, Figure 1 is a view in perspective showing a construction of suspension device embodying the principles of my invention as applied to a catenary suspension for trolley wires. Fig. 2 is a detail view in side elevation of the insulator employed in connection with a suspension device of my invention. Fig. 3 is a view in 30 section on the line 3—3, Fig. 2, looking in the direction of the arrows. Figs. 4, 5 and 9 are views in central longitudinal section of modified forms of insulator embraced within the spirit and scope of my invention. Fig. 40 6 is a view similar to Fig. 1, showing the application of my invention to the suspension of trolley wires direct from the insulator. Figs. 7 and 8 are views showing the application of a suspension device embodying the principles of my invention, and means for bracing the trolley wire or other conductor.

The same part is designated by the same reference sign wherever it occurs throughout the several views.

45 In the use of electric currents of high voltage for the operation of electric cars or other purposes, it is desirable to support the trolley wire or other conductor in such manner that it will be efficiently insulated. It

is also desirable in some instances to support the trolley wire or other conductor with as few sags or dips as possible, thereby producing a more nearly straight condition of the trolley wire, for instance, for the trolley wheel to travel along. This is important in the case where high speed of the car is desired. It is also desirable to support the trolley wire at frequent intervals as a 50 precaution for the safety of the public in case the trolley wire should break or fall. This is especially true where the trolley wire or conductor carries a current of high voltage. It is also desirable to provide a construction of suspension device of the nature 55 referred to which is inexpensive in manufacture, and which may be applied to change over the constructions at present in use for supporting or suspending trolley wires carrying current of low voltage to a system 60 designed for carrying current of high voltage. The attainment of these and other desirable objects by a construction which is simple, 65 efficient and economical of manufacture is among the special purposes of my present 70 invention.

In the drawings reference-sign A designates a post, designed to be placed between or to one side of the tracks of an electric railway roadbed and from which the trolley 75 wire is to be supported, in case of the use of my invention in connection with street cars, or as a support for the conductor in case my invention is to be used for other purposes.

B is a bracket or arm arranged to be supported upon the post A, and to extend horizontally therefrom. This arm or bracket may be of any suitable shape or construction. In the drawings I have shown this arm or bracket of tubular form, but I do 80 not desire to be limited or restricted in this respect. This arm or bracket may be supported upon the post A in any suitable or 85 convenient manner, as, for instance, by means of a casting C secured to the post A, 90 and provided with a socket in which the end of the arm or bracket B is inserted and clamped or held in any suitable or 95 convenient manner, as, for instance, by means of the set screw D.

If desired, the arm or bracket B may be braced to the post A in any suitable manner; for instance, and as shown in Figs. 1 and 6, a brace rod E is connected at one end to a casting F, secured to the arm or bracket B, 100 and at the other end to the post A.

and at the other end to the post A. This brace rod may be arranged above the bracket or arm B as shown in Figs. 1, 6 and 7, or, if desired, a brace rod G connected at one end 5 to a casting H on the post A, and at the other end to a casting J on the arm or bracket B, said brace-rod G being located below the arm or bracket B. Upon the outer end of the arm or bracket B is received 10 an insulator K.

In practice, and preferably, the insulator is provided with a central bore longitudinally therethrough, through which the end of the arm or bracket B is designed to be 15 slipped, the insulator being held against endwise movement upon the arm or bracket B in any suitable or convenient manner, as, for instance, by means of collars L suitably secured upon the arm or bracket B.

20 The insulator K may be of any suitable material such as porcelain or other insulating material, and the specific construction of the insulator may be varied throughout a wide range without departure from the 25 spirit and scope of my invention, the essential feature being the provision of an insulator adapted to support either directly or indirectly a messenger wire from which a trolley wire or other conductor may be suspended or supported, or else adapted to suspend the trolley wire or other conductor directly, as will appear more fully hereinafter.

It is obvious that the messenger wire, trolley wire or other conductor may be suspended 30 from or supported by the insulator K in many specifically different ways. For instance, in the drawing in Figs. 1, 2, 3, 6, 7 and 8 I have shown the insulator K provided with a central peripheral groove or 35 seat, indicated at M, (see Fig. 5,) in which is received the arms N O of a casting, said arms being clamped together by a bolt or otherwise, as indicated at P, at one end thereof, and at the other end being pivoted or 45 otherwise connected together by a pin Q, from which pin may be suspended a clamping device or hanger. This hanger or clamp device may be of any suitable or convenient type or construction.

50 In Figs. 1, 3, 7 and 8 I have shown a straight wire hanger R of ordinary construction, designed to be suspended from the bolt or pin Q, and to receive and support a trolley wire or conductor or messenger wire, 55 from which the trolley wire or conductor may in turn be suspended. In Figs. 1, 7 and 8 I have shown the hanger R supporting a messenger wire S, but it is obvious that the trolley wire or conductor might with equal 60 facility be carried or supported by the hanger R. In Fig. 6 I have shown a clamp device T of somewhat different construction suspended from the clamp band which is applied to the insulator K, but which clamp device may be of ordinary or standard con-

struction designed to clamp and suspend directly a trolley wire or other conductor A'. It is obvious, however, that a clamp device of the construction shown in Fig. 6 at T may with equal facility be employed to suspend a messenger wire instead of a trolley wire or other conductor, and such trolley wire or other conductor suspended from the messenger wire in any suitable or convenient manner, as, for instance, by means of suspending rods B', (see Fig. 1) connecting a hanger device R and a clamp device T, respectively connected to the messenger wire S and trolley wire A'. It is obvious, however, that the hanger device R and clamp device T may be interchanged, or a hanger device or a clamp device employed for connecting the suspending rod B' to both the messenger wire and to the trolley wire or other conductor, and it is also obvious that the 75 particular and specific construction of the clamp device or hanger used is unimportant, so far as the principles of my invention are concerned. It will be understood, of course, that in the messenger wire construction the 80 trolley wire or other conductor will be suspended from the messenger wire at frequent intervals, whereas the messenger wire will be supported or suspended by or from the insulator K on the brackets or arms B only 85 at the intervals of the posts A along the roadway.

In Fig. 4 I have shown a modified form of insulator K', having a central peripheral groove or seat M', and a longitudinal central bore C' therethrough to be sleeved upon the end of arm or bracket B.

In Fig. 9 I have shown another modified form of insulator K², provided with a central peripheral groove or seat similar to the groove or seat M of the construction shown in Fig. 5, and a longitudinal central bore similar to the central bore C' of the construction shown in Fig. 4, so as to enable the same to be sleeved upon the end of the arm or bracket B. The form shown in Fig. 9 is more nearly cylindrical in shape than the form shown in the other figures of the drawing, and for this reason is economical in manufacture. It is obvious, however, that 100 many other specifically different forms or shapes of insulator may equally well answer the purpose. I do not desire, therefore, to be limited or restricted to the exact details of construction of insulator.

Instead of suspending the messenger wire, trolley wire or other conductor by means of a strap or band, such as N, O, and a suspending hanger or clamp R or T, such wire or conductor may be suspended in any other 105 suitable or convenient manner from the insulator, as, for instance, by means of a wire or rod D', as shown in Fig. 5, said wire or rod D' passing around the conductor or trolley or messenger wire and also around the 110

insulator. It is also obvious that, if desired, the messenger wire may rest upon the insulator and be held thereon against danger of accidental displacement from its seat in the insulator in any suitable or convenient manner, as, for instance, by the weight of the trolley wire or other conductor suspended therefrom, or, if desired, by a wire similar to wire D', shown in Fig. 5. In such event the wire S shown in Fig. 5 would be at the top of the insulator, instead of at the bottom portion thereof as indicated in Fig. 5.

It is sometimes desirable to brace the trolley wire to prevent the same from swaying under the influence of the wind, and whether the trolley wire is suspended directly from the insulator or is suspended from a messenger wire. The necessity for bracing the trolley wire against lateral swaying is, however, present to a greater degree in the case of the messenger wire construction than in the case where the trolley wire is supported upon or suspended directly from the insulator. It is especially desirable to so brace the trolley wire whether supported upon or suspended directly from the insulator or from a messenger wire at curves in the roadway, and particularly where the trolley wire is suspended from a messenger wire, in which case the trolley wire is liable to be pulled over too far by the cross-braces or pull-over wires.

It is also among the special purposes of my invention to provide a construction for suitably bracing the trolley wire against being pulled over out of proper alignment with the roadbed, and this object may be accomplished in many different ways, and in Figs. 7 and 8 I have shown an application 40 of my invention in various ways to the accomplishment of these objects. In Fig. 7 I have shown an insulator K', similar in all respects to insulator K, and having a band strapped around the central part 45 thereof similar to the band comprising the arms N and O of Fig. 3, and from which is suspended a fitting T', to which is connected a brace arm E', said brace arm being connected by means of a clamp T² to the trolley 50 wire A'. In this instance the insulator K' is placed upon the brace G arranged beneath the arm or bar B and bracing the same from the post A, said insulator being held thereon by collars L', similar to the 55 collars L for holding the insulator K on arm or bracket B. It is obvious, however, that the insulator K' and sleeves L' may be otherwise suitably supported; for instance, in Fig. 8 I have shown the insulator 60 mounted directly upon the arm B, and connected through brace arm E' and clamp device T² to the trolley wire A'. In this instance the under brace G is dispensed with.

It is obvious that many variations and 65 changes in the details of construction and

arrangement would readily occur to persons skilled in the art and still fall within the spirit and scope of my invention. I do not desire, therefore, to be limited or restricted to the exact details of construction shown 70 and described. But

Having now set forth the object and nature of my invention, and a construction embodying the principles thereof, what I claim as new and useful and of my own invention, and desire to secure by Letters Patent, is:

1. In a suspension device for trolley or other wires or conductors, an arm or bracket, an insulator sleeved thereon, a trolley or 80 other wire or conductor supported by said insulator, and an insulated brace rod connected to said wire or conductor.

2. In a suspension device for trolley or other wires or conductors, an arm or bracket, 85 an insulator sleeved upon said arm or bracket, a trolley or other wire or conductor supported by said insulator, an auxiliary insulator, and a brace rod connected to said auxiliary insulator and to said wire or conductor.

3. In a suspension device for trolley or other wires or conductors, an arm or bracket, an insulator sleeved thereon, an auxiliary insulator also sleeved upon said arm or 95 bracket, a trolley or other wire or conductor supported by said first-mentioned insulator, and a brace rod connected respectively to said auxiliary insulator and to the trolley or other wire or conductor.

4. In a suspension device for trolley or other wires or conductors, an arm or bracket, an insulator sleeved thereon, a messenger wire supported by said insulator, a trolley or other wire or conductor suspended from said messenger wire, an auxiliary insulator, and a brace rod respectively connected to said auxiliary insulator and said trolley or other wire or conductor.

5. In a suspension device for trolley or 110 other wires or conductors, an arm or bracket, means for supporting the same, an insulator carried by said arm or bracket, a messenger wire supported by said insulator, a trolley or other wire or conductor suspended from 115 said messenger wire, an auxiliary insulator also mounted on said arm or bracket, and a brace rod respectively connected to said auxiliary insulator and to said trolley or other wire or conductor.

6. The combination with a supporting post, an arm or bracket supported at one end by said post, a brace connecting said arm or bracket and post, an insulator sleeve upon the free end of said arm or bracket, a trolley or other wire or conductor supported from 125 said insulator, and means for bracing said trolley or other wire.

7. The combination with a supporting post, an arm or bracket supported at one end 130

- upon said post, a brace connecting said arm or bracket and said post, an insulator sleeved upon said arm or bracket, a messenger wire supported by said insulator, a trolley or other wire or conductor suspended from said messenger wire, and means for bracing said trolley or other wire or conductor.
8. In a suspension device for trolley wires or other conductors, an arm or bracket and means for supporting the same, in combination with a sleeve composed of insulating material into which said bracket passes, means passing around said sleeve for supporting a trolley wire or conductor, and adjustable means on the bracket for holding the sleeve against longitudinal movement thereon.
9. In a suspension device for trolley wires or other conductors, an arm or bracket, means for supporting the same, in combination with a sleeve composed of insulating material, and through which said bracket passes, the outer or free end of said bracket being of uniform diameter, whereby the sleeve may be adjusted longitudinally on said arm, the sleeve having means for supporting a trolley wire and holding the wire against movement longitudinally of the sleeve, and adjustable means for holding the sleeve against movement longitudinally on said arm.
10. In a suspension device for trolley wires or other conductors, an arm or bracket, and means for supporting the same in substantially a horizontal position, in combination with a sleeve composed of insulating material, through which said arm passes, the outer or free end of said arm being of smaller diameter than the passage through the sleeve, whereby the sleeve may be slipped over the outer end of the arm after the arm is fixed in place, or may be removed therefrom, and means for holding the sleeve against longitudinal movement on the arm.
11. In a suspension device for trolley wires the combination with a supporting post, of a bracket support at one end of said post, a brace rod supporting said bracket on the post, an insulator sleeved upon the free end of said bracket, a messenger wire supported by said sleeve and a trolley wire or other conductor suspended from said messenger wire.
12. In an overhead structure for electric

railways, the combination with a pole and an arm projecting laterally therefrom, an inclined brace rod between said arm and 55 said pole, insulators adjustably mounted upon the laterally projecting arm, a messenger cable suspended from one of said insulators, a trolley conductor suspended from said messenger cable and a steadyng rod 60 extending between the trolley conductor and the other insulator.

13. In an overhead structure for electric railways, a trolley conductor, a messenger wire or cable from which the trolley conductor is suspended, a supporting structure embodying adjustable insulators, means for suspending the messenger wire or cable from one of said insulators, and a steadyng rod 65 between the trolley conductor and the other insulator.

14. The combination with an approximately horizontal rod or bar, of a circumferentially grooved, tubular insulator that is so mounted upon said arm or bar as to be 75 longitudinally adjustable, and means for detachably clamping the insulator in any position to which it may be adjusted.

15. The combination with a circumferentially grooved insulator having a hole extending longitudinally through it, of a supporting member of less diameter than said hole upon which the insulator is mounted and means for clamping the insulator in any position to which it may be longitudinally 80 adjusted.

16. A cylindrical porcelain insulator for an electric conductor having one or more circumferential grooves and provided with means for so clamping it to an internal support that it may be longitudinally adjusted 85 thereon.

17. A tubular insulator having circumferential ridges and means for so clamping it to a supporting arm or bar that it may be 90 longitudinally adjustable.

In witness whereof, I have hereunto set my hand this 29th day of November 1904, in the presence of the subscribing witnesses,

GEORGE A. MEAD.
